UNITED STATES PATENT OFFICE.

GEORGE ROE MEREWETHER, OF HULL, QUEBEC, CANADA, ASSIGNOR OF ONE-HALF
TO THE E. B. EDDY COMPANY, LIMITED, OF HULL, QUEBEC, CANADA.

SAFETY BLOW-OFF DEVICE FOR DIGESTERS AND THE LIKE.

1,088,162.

Specification of Letters Patent. Patented Feb. 24, 1914.

Application filed April 7, 1913. Serial No. 759,529.

To all whom it may concern:

Be it known that I, GEORGE ROE MEREWETHER, a subject of the King of Great Britain, residing at Hull, in the Province of Quebec, in the Dominion of Canada, have invented certain new and useful Improvements in Safety Blow-Off Devices for Digesters and the like, of which the following is the specification.

10 This invention relates to safety blow-off devices for digesters and the like, and the objects are to provide a device of this kind which may be relied upon to permit a digester to blow off whenever the pressure becomes excessive.

It is quite usual to provide safety valves on digesters used in paper making and the like. The difficulty with such safety valves is that the gum and other material exuded 20 from the wood during the operation of the digester collects on the seat of such safety valve and causes the valve to adhere to the seat so that the valve will not relieve the digester at the required pressure. The present invention overcomes these difficulties by 25 providing a liquid seal of mercury or like heavy liquid adapted to be blown by excessive pressure into a suitable collector, all as hereinafter more fully set forth and described in the accompanying specification and drawing.

The drawing shows a sectional elevation of the apparatus forming the present invention.

35 Referring to the drawing, A represents a digester or the like of well known construction.

B represents liquid containing means in the form of a U-shaped tube connected by 40 a pipe 10 with the top of the digester, the connection between the pipe 10 and the digester being controlled by a valve 11 which is normally left open. The U-shaped tube is normally filled to a given height with 45 heavy liquid such as mercury, the tube being relatively narrow so that considerable pressure will be required on the digester side to expel the mercury from the U-shaped tube.

50 The opposite side of the tube B to that which is connected to the digester leads to a collecting member C which has an outlet pipe or chimney 12 for the steam and other gases discharged from the digester. The 55 collecting member is formed with a cylin-

drical collecting chamber 13 in which the mercury collects, the said chamber being connected by two short tubes 14 and 15 with unions 16 and 17, said unions being connected with short sections of tubes 18 and 19 with a T 20 from which the pipe 12 leads.

The mercury may be withdrawn, if necessary, through a suitable stop cock 30.

The U-shaped tube B is connected by a pipe 21 with the union 17, and the T 20 is 65 formed on the interior with an inclined baffle plate 22 against which the discharging gases from the digester impinge, said baffle plate being adapted to deflect the gases downwardly and prevent too rapid discharge through the outlet 12 and also to prevent loss of mercury in this way. From the lower part of the collecting chamber 13 a pipe 24 leads to the U-shaped tube B, the flow of liquid through the tube being controlled by a suitable valve 25 normally kept closed.

If desired, the resistance offered by the liquid in the U-shaped tube may be increased by a suitable safety valve 32 placed in the 80 U-shaped tube and on the opposite side thereof to that to which the digester is connected.

The operation of the device is as follows:—The valve 11 is normally kept open 85 and the valve 25 closed. When any excessive pressure is created in the digester A the mercury contained in the tube B will be discharged through the pipe 21 into the collecting member and will flow through the 90 pipes 14 and 15 into the collecting chamber 13, leaving an unobstructed passageway from the digester to the outlet pipe 12 and through which the digester may blow off.

As soon as the digester has been sufficiently relieved, the valve 11 is closed and the valve 25 opened, permitting the mercury to flow back into the U-tube B; thereupon the valve 25 is closed, the valve 11 opened and normal conditions thereby restored.

As many changes could be made in the above construction and many apparently widely different embodiments of my invention within the scope of the claims, constructed without departing from the spirit or scope thereof, it is intended that all matter contained in the accompanying specification and drawings, shall be interpreted as 105 illustrative and not in a limiting sense. 110

What I claim as my invention is:

1. A safety blow-off device for digesters, comprising a U-shaped tube containing a heavy liquid connected at one side to the digester, a collecting member comprising a collecting chamber, upwardly extending pipes thereon, unions connected to the pipes, a T, tubes connecting the T with the unions, a pipe connecting one of the unions with the U-shaped tube and an outlet pipe leading from the T.
- 10 2. A safety blow-off device for digesters, comprising a U-shaped tube containing a heavy liquid connected at one side to the digester, a collecting member comprising a collecting chamber, upwardly extending pipes thereon, unions connected to the pipes, a T, tubes connecting the T with the unions, a pipe connecting one of the unions with the U-shaped tube and an outlet pipe leading from the T, and a baffle plate in the T.
- 15 3. A safety blow-off device for digesters, comprising a U-shaped tube containing a heavy liquid connected at one side to the digester, a collecting member comprising a collecting chamber, upwardly extending pipes thereon, unions connected to the pipes,
- 20 25

a T, tubes connecting the T with the unions, a pipe connecting one of the unions with the U-shaped tube and an outlet pipe leading from the T, and a valve pipe connecting the collecting chamber with the U-shaped tube.

4. A safety blow-off device for digesters comprising a U-shaped tube containing a heavy liquid connected at one side to the digester, a collecting member comprising a collecting chamber, upwardly extending pipes thereon, unions connected to the pipes, a T, tubes connecting the T with the unions, a pipe connecting one of the unions with the U-shaped tube and an outlet pipe leading from the T, and a valve pipe connecting the collecting chamber with the U-shaped tube and means of increasing the resistance offered by the liquid in the said U-shaped tube consisting of a valve located in the pipe connecting one of the unions with the said U-shaped tube.

In witness whereof I have hereunto set my hand in the presence of two witnesses.

GEORGE ROE MEREWETHER.
